UNITED STATES PATENT OFFICE.

EDWARD A. CUNNIFF, OF WALTHAM, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Application filed December 27, 1926. Serial No. 157,151.

This invention relates to filling replenishing looms and is more particularly directed to the feeler mechanisms of such looms, whereby, on substantial exhaustion of filling, the operative condition of the loom is changed, such, for instance as replenishment of filling.

It is now the ordinary practice to provide filling replenishing looms with feeler mechanisms to effect replenishment of filling upon substantial exhaustion of filling in the loom shuttle, and such feeler mechanisms are usually located at the non-replenishing side of the loom. In some cases it is desirable to place the feeler mechanism at the replenishing side of the loom and this has heretofore been suggested. In the use of feeler mechanisms of the side slipping type which have lately come into extensive use, certain problems are presented when such feeler mechanisms are located at the replenishing side of the loom.

The Brown & Repass Patent, No. 1,593,426, dated July 20, 1926, shows and describes a side slipping feeler mechanism which has proven to be delicate and sensitive, both as to the presence and substantial absence of filling, and especially is this observable in weaving with certain kinds or characters of filling. In the Brown & Repass feeler mechanism, the feeler itself normally stands for engagement with the filling at substantially right angles to the axis of the filling carrier or shuttle and is held from side slipping movement by engagement therewith, but when filling is substantially exhausted on a detecting beat, the feeler readily side slips and through a train of transmitting mechanism replenishment of filling is called.

The feeler mechanism of the Brown & Repass patent is shown and described as applied to the non-replenishing side of the loom, and one of the objects of the present invention is a further development of such feeler mechanism whereby it may be applied to the replenishing side of the loom, while utilizing the advantages of its sensitive character both as to the presence and substantial absence of filling in the shuttle.

The invention, new features thereof and novel combination of parts will best be made clear from the following description and the accompanying drawings of one good form thereof.

In the drawings:

Fig. 1 is a perspective view of portions of the loom at the replenishing side, showing the present invention applied thereto;

Fig. 2 is an enlarged detail with parts broken away and others omitted for the purposes of clearness, showing the action of the feeler mechanism at the replenishing side of the loom when filling is substantially exhausted on a detecting beat; and

Fig. 3 is a similar view but showing the feeler withdrawn from the shuttle at the time of filling replenishment.

The present illustration of the invention includes a train of mechanism for effecting replenishment of filling when the shuttle is in the replenishing box, but since the detail of such replenishing mechanism forms no essential part of the present invention and is now understood in the art, its full illustration and description appears unnecessary.

As usual in filling replenishing looms, a hopper or magazine is employed for containing the filling carriers having filling wound thereon, and while such hopper or magazine may be of any usual type, it is herein shown as of the rotary character.

The loom frame which may be of usual construction has mounted thereon the hopper stand 1 for supporting the rotary hopper 2 in which the filling carriers 3 are mounted and successively brought to transferring position as usual in this character of loom. Mounted upon the hopper stand is the stud or shaft 4 on which is mounted the transerrer 5 from the hub portion 6 of which an arm 7 extends downwardly and has pivotally connected thereto the dog 8, the rear end portion of which is adapted at times to be engaged by a bunter 9 carried by the lay 10 to thereby actuate the transerrer 5 to transfer a fresh filling carrier to the shuttle and eject the denuded filling carrier. The transerrer is normally under the influence of a spring 11 which is shown as coiled about the axis of the transerrer and normally acting to maintain the transerrer in its raised or inoperative position ready for transferring a filling carrier from the hopper to the shuttle.

The shuttle 12 may be of usual character common in filling replenishing looms, and is provided with the bobbin holding jaws 13. The front wall of the shuttle is provided

with an opening 14 which registers with the corresponding opening 15 in the front wall of the shuttle box when the shuttle is in replenishing position to thereby permit the 5 feeler to feel for filling in the shuttle on a detecting beat. All of these parts thus far described may be of usual construction and need no further explanation.

Mounted upon the loom frame or an extension therefrom is the support 16, Fig. 1, which may be appropriately secured to the loom frame by an appropriate pin or threaded bolt 17, and such support has a guideway 18 extending towards the rear of the loom, 10 as more clearly shown in Figs. 2 and 3. Mounted for sliding movement towards and from the front of the loom in the guideway 18 is the slide 19 which is normally pressed rearwardly by yielding means such as a 15 spring. In the present instance of the invention the slide 19 is provided with an upwardly extending abutment or lug 20 in which is mounted the pin 21 which may be secured to the lug 20 by a suitable nut 22. 20 Coiled about the pin 21 is a spring 23, the rear end portion of which bears against the abutment 20 and the front end portion of which bears against the front wall 24 of a cap piece 25 secured by a bolt 26 to the support 16. The pin 21 extends frontwardly and passes through an opening in the front wall of the cap, the result being that the slide 19 is normally held yieldingly in its rearward position and is limited in its rearward position by an adjusting bolt 27 which 25 may be threaded into a laterally projecting arm 28 carried by the slide 19 and adapted when the slide 19 is in its rearward position to bear against the lug 29 connected to the support 16. If desired, the horizontal position of the support 16 may be appropriately 30 adjusted by a threaded bolt 30, Fig. 1, passing through a lug 31 secured to the loom frame or a part carried thereby, and bearing 35 on the under side of the support 16. The support 16 is normally under the influence of a spring 32 for holding the parts in their adjusted position.

Mounted upon the slide 19 is a feeler stand 33 which may be held to the slide by suitable means such as the pins or bolts 34, as more clearly indicated in Figs. 2 and 3.

The feeler stand 33 carries a non-pivoted floating feeler 35, the rear end portion of which is provided with teeth 36 for engagement with the filling on detecting beats, and extending laterally from the feeler 35 is an arm 37, the end 38 of which is adapted at times to engage a stop or bearing 39 formed 40 on the feeler stand. The feeler 35 is normally under the influence of a spring 40, one end of which is connected to a lug 41 on the feeler stand and the other end of which is connected to the arm 37 at 42, between the 45 end of the laterally extending arm 37 and the

feeler 35, the construction being such that the spring 40 normally tends to move the feeler rearwardly, and yet permits it to move forwardly and partake of its side swipe movement, as will more fully appear from 50 the Brown & Repass patent to which reference has been made.

The feeler stand is provided with a second stop or bearing 43 against which the feeler 35 rests when the feeler is in its extended 55 position relative to the feeler stand, as indicated in Fig. 3.

The forwardly extending portion of the feeler 35 has a heel 44 which in connection with the end of the arm 37 acts to guide the feeler in its forward and rearward movements along the guideways 45, 46 of the feeler stand during weaving with a working supply of filling in the shuttle, and the heel 44 is slightly offset from the lengthwise axis 60 of the feeler 35 to permit the feeler to side swipe to the extent of the slot or opening 46 in the feeler stand when the filling is substantially exhausted on a detecting beat. The feeler as herein described may be substantially the same both in construction and mode of operation as that shown and described in the Brown & Repass patent above referred to.

Mounted upon the loom frame or a part 65 affixed thereto is a bracket 47, Fig. 1, which is provided with an upwardly extending slot 48 in which works the end 49 of an actuator 50, which may be of usual and well-known construction.

Extending crosswise of the slot is a bracket 51 having a boss 52 provided with an opening into which extends a pin 53 connected at 54 to the forwardly extending arm 55 of a lever 56 pivotally mounted at 57 on a 105 bracket 58 which may be appropriately secured by a bolt 59 to the bracket 47. The rearwardly extending arm of the lever 56 is connected at 60 to a transmitter 61, the opposite end portion of which is loosely engaged 110 with the feeler 35, as at 62, the construction being such that should the feeler 35 partake of its side slipping movement, as indicated in Fig. 2, the transmitter 61 will be moved laterally to thereby rock the lever 56 and interpose the pin 53 into the path of the actuator 50 which thereby acts through a 115 train of mechanism of well-known construction to effect replenishment of filling.

In order that the transerrer may operate to transfer a fresh filling carrier from the hopper to the shuttle when the feeler itself has side slipped to call for replenishment, it becomes necessary to withdraw the feeler from the shuttle to permit the fresh filling carrier to enter, and as such feeler is withdrawn from the shuttle and consequently is relieved of the pressure of the filling carrier, the spring 40 will act upon the feeler to again straighten it or place it in 125 130

position at substantially right angles to the axis of the filling carrier or bobbin.

As hereinbefore stated, the dog 8 is pivotally connected to the downwardly extending 5 arm 7 of the transerrer, as indicated in Fig. 1, and the pin connection between the two, as at 63, is extended laterally to engage a lug 64 projecting from the slide 19 when the transerrer is actuated to effect the transfer, 10 a condition which is indicated in Fig. 3.

During weaving with a working supply of filling in the shuttle, as indicated in Fig. 1, the floating side slipping feeler 35 will engage the filling in the shuttle at substantially right angles thereto and will be moved 15 frontwardly against the action of the spring 40, the teeth of the feeler at such times maintaining the feeler from side slipping movement. As the feeler thus moves frontwardly 20 it slides through the end portion 62 of the transmitter 61, which is shown as not secured to the feeler stand, and on retreat of the lay after a detecting beat up the feeler will return to its rearward feeling position 25 to again engage the filling on a detecting beat at right angles to the axis of the filling carrier. The result of this right angled engagement of the feeler with the filling relieves the filling, even though it be of delicate nature, from any injurious influences. 30

When the filling is substantially exhausted on a detecting beat, the feeler 35 side slips along the filling carrier in the shuttle into the position indicated in Fig. 2, thereby 35 acting through the transmitter 61 to interpose the pin 53 into the path of the actuator 50, with the result that filling replenishment will be called, and as the dog 8 is pushed frontwardly by the bunter 9, the pin 63 will 40 engage the projection 64 on the slide 19 and withdraw the slide and with it the feeler stand and feeler frontwardly to thereby withdraw the feeler from the shuttle to permit the entrance of the fresh filling carrier, 45 as indicated in Fig. 3. As the feeler is thus withdrawn from the shuttle by frontward movement of the feeler stand, the feeler is moved rearwardly on the stand under the influence of the spring 40 and by reason of 50 the fulcrum stops 39 and 43 will assume a position at right angles to the longitudinal axis of the filling carrier in the shuttle, a position it will maintain as the feeler stand again moves rearwardly on completion of replenishment of filling. 55

The feeler stand is provided with a cover plate 65 which may be appropriately secured to the feeler stand by means of bolts 34, as indicated in Fig. 1, and thereby serves 60 to maintain the floating feeler within the feeler stand during its frontward and rearward side slipping movements.

From the construction described it will be obvious that the present invention adapts 65 the sensitive feeler mechanism of the Brown

& Repass patent for use at the replenishing side of the loom, thereby securing the advantages of such feeler mechanism in its association with the filling replenishing shuttle box into which the feeler may extend to feel for the filling at right angles thereto. 70

What is claimed is:

1. In a feeler mechanism for looms, the combination of a feeler stand mounted at 75 the filling replenishing side of the loom, a floating side slipping feeler non-pivotaly mounted for bodily movement on the feeler stand towards and from the front of the loom on detecting beats with a working supply of filling in the shuttle and for side slipping movement longitudinally of the shuttle due to the pressure of the filling carrier when the filling is substantially exhausted, a transmitter connected to the 80 feeler back of the feeler stand, a lever pivoted between its ends and having one end connected to the transmitter, a pin extending from the other end of the lever, an actuator into the path of movement of which the pin 85 is projected when the feeler side slips and by which it is arrested to effect replenishment of filling and means for withdrawing the floating feeler from the shuttle on replenishment of filling. 90

2. In a feeler mechanism for looms, the combination of a feeler stand at the replenishing side of the loom, a floating side slipping feeler mounted for bodily movement on the feeler stand towards and from the front 100 of the loom and for side slipping movement longitudinally of the shuttle by the frontward pressure when the filling is substantially exhausted on a detecting beat, a transmitter connected to the feeler back of the 105 feeler stand, a bracket having an upwardly extending slot, an actuator working in said slot, a lever mounted on the bracket rearward of the slot and having an arm connected to the transmitter, a pin extending 110 from the other arm of the lever, a guide for the pin crossing said slot for directing the pin into the path of movement of the actuator upon side slipping movement of the feeler, means for holding the feeler stand 115 in a rearward position during weaving with a working supply of filling in the shuttle, and means for withdrawing the feeler stand frontwardly on replenishment of filling to withdrawn the floating feeler from the 120 shuttle. 125

3. In a feeler mechanism for looms, the combination of a feeler stand at the replenishing side of the loom, a floating side slipping feeler mounted on the feeler stand for movement relative thereto towards and from the front of the loom and in a direction longitudinally of the shuttle and held from side slipping movement on detecting beats 130 by engagement with the filling until sub-

stantial exhaustion thereof, means normally acting to hold the floating feeler in its rearward feeling position, a bracket at the side of the feeler stand having a vertical slot, an actuator working in said slot, a lever pivotally supported between its ends and having a rearwardly extending arm, a transmitter connected to said arm and to the feeler, a pin carried by the forwardly extending arm of the lever opposite the slot and adapted to be moved into the side opening of the slot to arrest the actuator and effect replenishment of filling when the feeler side slips on substantial exhaustion of filling.

4. In a filling replenishing loom, the combination of a feeler stand at the replenishing side of the loom, a floating side slipping feeler supported upon the feeler stand for bodily sliding movement thereon directly towards and from the front of the loom on detecting beats with a working supply of filling in the shuttle and for side slipping movement thereon due to the frontward pressure when the filling is substantially exhausted, an actuator, a transmitter connected to and extending laterally from an intermediate portion of the feeler, a lever connected to the other end of the transmitter and provided with a pin adapted to be projected into the path of the actuator when the feeler side slips and moves the transmitter laterally, means set in operation by such side slipping movement of the feeler for effecting replenishment of filling, and means for withdrawing the floating feeler from the shuttle after its side displacement by the frontward pressure to permit replenishment of filling.

nected to said lever and to the feeler for projecting the pin into the side opening of the slot and stopping the actuator when the feeler side slips on substantial exhaustion of filling.

5. In a filling replenishing loom, the combination of a feeler stand at the replenishing side of the loom, a floating side slipping feeler supported upon the feeler stand for bodily sliding movement thereon directly towards and from the front of the loom on detecting beats with a working supply of filling in the shuttle and for side slipping movement thereon due to the frontward pressure when the filling is substantially exhausted, an actuator, a transmitter connected to and extending laterally from an intermediate portion of the feeler, a lever connected to the other end of the transmitter and provided with a pin adapted to be projected into the path of the actuator when the feeler side slips and moves the transmitter laterally, means set in operation by such side slipping movement of the feeler for effecting replenishment of filling, and means for withdrawing the floating feeler from the shuttle after its side displacement by the frontward pressure to permit replenishment of filling.

In testimony whereof, I have signed my name to this specification.

EDWARD A. CUNNIF. 60
